ELECTRICAL CONNECTOR

Harry W. Earl, South Miami, Fla.

Application May 24, 1956, Serial No. 587,086

3 Claims. (Cl. 339—149)

This invention relates to electrical connectors and is more particularly directed to separable connectors for electrical conductors for use with industrial equipment requiring heavy electrical current.

This invention is an improvement of the connector shown and described in my copending application Serial Number 374,917, filed on August 18, 1953, entitled Electrical Conector, issued on February 5, 1957, Patent No. 2,780,792.

A principal object of the present invention is to provide electrical connectors having a male and female unit telescopically fitting together to effect a secured, frictional contact which provides proper conductivity without loss to the flow of electricity therethrough.

A further object of the present invention is the provision of electrical connectors as described above which cannot be inadvertently separated yet is readily connected and just as readily disconnected by a simple, easy twisting action of one part of the connector relative to the other.

A further object of the present invention is to provide a separable electrical connector for the transmission of heavy currents which provides large contacting surfaces that are in tight contacting relation at all times thereby reducing current losses to a minimum.

A still further object of the present invention is the provision of separable electrical connectors characterized as above which are simple and inexpensive in construction and readily mounted on electrical cables or conductors.

With these and other objects in view, the invention will be best understood from a consideration of the following detailed description taken in connection with the accompanying drawing forming a part of this specification, with the understanding, however, that the invention is not confined to any strict conformity with the showing of the drawing but may be changed or modified so long as such changes or modifications mark no material departure from the salient features of the invention as expressed in the appended claims.

In the drawing:

Figure 1 is a side elevational view of an electrical connector partially broken away, showing a male and female unit in their connected position.

Figure 2 is a longitudinal sectional view taken along the line 2—2 of Figure 1.

Figure 3 is an enlarged fragmentary view of the male and female units at their position of contact.

Figure 4 is a similar view to that shown by Figure 3 with the male and female units interlocked upon twisting or rotating one unit relative to the other.

Figure 5 is an enlarged fragmentary view showing the interlocking action between the male and female units.

Referring to the drawing wherein like numerals are used to designate similar parts throughout the several views, the numerals 10 and 11 refer to a male and female unit respectively, which constitute the electrical connector embodying my invention.

2

The male unit 10 consists of a tubular member 12, constructed preferably of drawn copper though any electrical conducting metal may be used, having a further tubular member 13 telescopically mounted and secured therein. That portion of the tubular member 13 which extends beyond the end of the tubular member 12 is slotted longitudinally as at 14, 14. The free end 15 of the tubular member 13 has its inner surface 16 tapered while the remainder of the tubular member 13 is of constant diameter throughout. A cable 17 with its insulation removed a short distance of the end thereof extends within the tubular member 13 opposite to the end 15 and is secured therein by bolts 18 threaded through the side walls of the tubular members 12 and 13 to clamp the cable 17 firmly therein. The cable 17 is in tight electrical contact engagement with the tubular member 13. A grip 20 made of rubber or the like having electrical insulating characteristics is fitted over the tubular member 12 and a portion of the insulated cable 17. The grip 20 is provided with a recessed portion 21 forming an annular lip 22 extending beyond the end of the tubular member 12. The bolts 18, 18 which extend through bores 22 formed in the grip 20 are countersunk therein so that they do not come into contact with a person handling the grip 20.

The female unit 11 consists of a rubber grip 24 similar somewhat to the grip 20 of the male unit 10 mounted on a tubular member 25 having the same diameter as tubular member 12 of the male unit 10. The grip 24 is likewise provided with an annular recess 26 forming a lip 27 similar to the lip 22 of the grip 20. An expander or plug 28 positioned within the tubular member 25 is hollow or tubular at one end 29 receiving an uncovered portion of an insulated cable 30 therein. Bolts 31 extending into bores 32 formed in the grip 24 are threaded through the side walls of the tubular member 25 and tubular portion 29 of the plug 28 to form electrical contact between the cable 30 with the tubular member 25 and the plug 28. The forward end 32 of the plug 28 is provided with a longitudinal slot 33 which extends to a position adjacent the tubular portion 29. The outer surface of the end 32 of the expander 28 is tapered as at 34 and an annular recess 35 is positioned inwardly of the tapered portion 34. The tapered surface 34 increases in diameter from the free end of the plug 32, the latter being slightly smaller than the inside diameter of the tubular member 13 of the male plug 10. The tapered surface 34 increases in diameter to the rear thereof so that the largest diameter thereof is slightly larger than the inside diameter of the tubular member 13 but less than the largest diameter of the tapered surface 16 of the tubular member 13.

The expander 28 provides a double function; first, it yieldingly forces the extension 15 of the tubular member 13 of the male unit 10 into full contact relation with the tubular member 25 of the female unit 11 so that electricity will flow therethrough without loss or cause heating of the various parts thereof; second, upon twisting the slots 14, 33 of the male and female units 10 and 11 out of alignment as explained in detail hereinafter, the outward pressure exerted by the expander 28 at its largest diameter on the extension 15 along its tapered surface 16 causes the extreme end thereof to spring or distend inwardly as at 36 as shown by Figure 5, and thereby lock the two members together.

With construction as indicated above and cable 30 connected to a source of electricity, the male and female units 10 and 11, respectively are grasped by a person and aligned by positioning the bolts 18, 18 in alignment with the bolts 31. This places the slots 14, 14 of the male unit 10 in alignment with the slot 33 of the expander or plug 28. The extension 15 of the tubular member 13 is then fitted in the tubular member 25 of the female unit

11 and permitted to be forced inwardly until the plug 28 is seated within the extension 15 as shown by Figure 3. In this position the extension 15 extends to the recess 35 and the expander 28 is forcibly urging the tubular member 13 into contact relation with the tubular member 25 and thereby providing a proper path for the flow of electricity therethrough. Also, as shown by Figure 3, the slots 14 of the tubular member 13 and the slot 33 which has become slightly compressed in alignment. The peripheral shape of the extension 32 of the plug 28 has changed from a circle to an oval due to the compression of the slot 33. Now, with the male and female units 10 and 11 in a person's grasp, the units 10 and 11 are each given a twisting force in the opposite directions causing the slots 14 to move out of alignment with the slot 33. Upon the rotation of the slightly oval shaped plug 32 a tremendously increased force is exerted by virtue of a cam action of the plug 32 on the extension 15 effecting a distention of the tubular extension 15 spreading diametrically opposite portions of the periphery of the extension 15 at the rear of the tapered portion of plug 28 more firmly against the inside of tubular member 25. It has been found that this twisting action while pushing the units 10 and 11 together, causes the corresponding diametrically opposite portions of the outer edges of extension 15 to bend inwardly from the distended portions into the recess 35, as shown in dotted lines in Fig. 5 at 36. The deformed edges of the extension 15 forms abutments or obstructions to prevent the plug 28 from being withdrawn from the tubular member 13 and the male and female units 10 and 11 from becoming inadvertently separated.

Now in order to break the separator by disconnecting the male unit 10 from the female unit 11, the male and female units are twisted until the bolts 18 and 31 are again in alignment thus bringing the slots 14 and 33 in alignment. With the plug 32 resuming its original position relative to that of the tubular member 13, the force exerted by the plug 28 is lessened and the extension 15 resumes its original shape, the distended portion 36 no longer extending itself inwardly in the direction of the recess 35. An outward pulling force is now exerted on each of the male and female units 10 and 11 until the plug 32 slides longitudinally out of the tubular member 13 to effect the complete separation of units 10 and 11.

Having thus described my invention, what I claim as new and desire to secure by Letters Patent is:

1. A separable electrical connector comprising a first tubular member having the inside surface of its outer end

tapered outwardly and a longitudinal slot on opposite walls extending along said outer end, a second tubular member having an inside diameter slidably fitting over the outside of said first tubular member, and an expander member having a base portion fixed in the inner end of said second tubular member and an enlarged extended portion with a diametrically slotted head positioned in spaced relation to the walls of said second tubular member, said head having a tapered surface matching the tapered inside surface at the outer end of said first tubular member for engagement therewith to form an extended surface contact when said tubular members are telescopically pushed together with said longitudinal slot and said head slot in substantial alignment, said head being sharply undercut at its rear, the largest taper diameter at the rear edge of said tapered head being thus moved inwardly past the thin edges of the outer end of said first tubular member and the head compressed to a slightly oval shape, while the outer end of said first tubular member is stretched to conform to this shape and provide firm contact pressure between the outer surface areas of said first tubular member, diametrically opposite the sides of said head slot, and the corresponding inner surface areas of said second tubular member; whereby upon relative twisting movement of said tubular members, abutments are formed in the edge of the outer end of said first tubular member inwardly against the rear of said tapered head to substantially lock said members against inadvertent contact relaxation.

2. A separable electrical connector as defined in claim 1, and a tubular hand grip made of insulated material for each of said tube members for manual operation of said connector.

3. A separable electrical connector as defined in claim 2, each hand grip having a sleeve of conducting material extending inwardly from the inner end of the corresponding tubular member for the reception of a cable end, and counter-sunk clamp screws in said grip threaded through said sleeve against said cable end at a circumferential position in said grip indicating the diametrical position of the corresponding slot to facilitate the substantial alignment of said slots in the connecting operation.
